METAL FORMING PRESS

Arne O. Andresen, Allen Park, Mich., assignor to Kropp Forge Company, Chicago, Ill., a corporation of Illinois

Application February 16, 1953, Serial No. 337,087

3 Claims. (Cl. 153—25)

This invention relates to improvements in metal forming presses and more particularly relates to such a press for finishing a partially formed article.

A principal object of my invention is to provide a novel and improved press of a simplified construction for performing a finishing forming operation on a partially formed article.

Another object of my invention is to provide a metal forming press having two cooperating holding dies conforming to and rigidly holding a partially finished article and having a forming die having a die face cooperating with a die face of one of the holding dies for performing a forming operation on the partially formed article.

Still another object of my invention is to provide a simple improved form of hydraulic press of a novel construction, having stationary and movable dies engageable with a partially finished article and holding the article free from distortion during a finish operation thereof, one of said holding dies having a die face extending at an angle to the article, and said press having a third die engageable with a projecting end of the article and forming the same to conform to the die face of said one die.

Still another object of my invention is to provide a hydraulic metal forming press having a fixed die with a die face adapted to supportingly receive a partially finished article and a movable die moved by fluid under pressure to hold the article into engagement with the die face of the fixed die, and also having a third die having a die face cooperating with the movable die, for bending the article into engagement therewith.

Still another object of my invention is to provide a novel and improved form of metal forming press for finish bending a forged link of a type forming a part of the tread of a continuous traction device wherein the link is rigidly held between two dies by fluid under pressure, and wherein a third hydraulically operated bending die is provided for cooperation with said two dies to place a predetermined bend on a projecting portion of the link.

A still further and more detailed object of my invention is to provide a rugged and efficient form of metal forming press having two side plates having a hydraulically operated holding die mounted therebetween, and having a hydraulically operated bending die guided in the side plates for movement therealong and vertically moved along side of the holding die to place a finish bend on a projecting portion of a forged article.

These and other objects of my invention will appear from time to time as the following specification proceeds and with reference to the accompanying drawings wherein:

Figure 1 is a view in side elevation of a metal forming press constructed in accordance with my invention;

Figure 2 is a front end view of the device shown in Figure 1;

Figure 3 is an enlarged fragmentary sectional view taken substantially along line III—III of Figure 2 and showing certain details of the bending and holding dies not shown in Figures 1 and 2;

2

Figure 4 is a fluid diagram showing the fluid connections for supplying fluid under pressure to the holding and bending dies;

Figure 5 is a view in side elevation of a link of a continuous traction tread device formed by the press of my invention; and

Figure 6 is a plan view of the link shown in Figure 5.

In the embodiment of my invention illustrated in the drawings, I have shown a press 10 mounted on a base 11, shown as being formed from structural members suitably connected together, as by welding. The rear end portion of the base 11 is shown as having a tank 12 mounted thereon. A motor 13 is shown as being mounted on the top of said tank and as driving a pump indicated generally by reference character 15.

The tank 12 and pump 15 form a source of supply of fluid under pressure for an upper holding cylinder 16 for engaging a holding die 17 with a partially formed article 18 and holding the article to a stationary die 19 for a finish bending operation on the article. The pump 15 also supplies fluid under pressure to a lower cylinder 21, moving a bending die 22 on a vertically guided plate 23, into engagement with a projecting end portion 24 of the article and cooperating with the die 17 to perform a finish bending operation on the article.

The article 18 is shown in Figures 4 and 5 as being a tread link of a continuous traction tread device. It should be understood, however, that while I have herein shown the article as being a link of a continuous traction tread device, that various other articles may be formed, particularly such articles where it is necessary to bend a part thereof at an angle to the main body thereof, after a forging and stripping operation of the article.

The stationary holding die 19 is shown as being mounted on the top surface of a die block 25 by means of cap screws 27, 27, extending through the die block 25 from the bottom thereof and threaded within said holding die 19. The die block 25 is shown as extending across and being recessed at its ends, within two parallel spaced vertically extending side plates 29, 29, of the press 11. Cap screws 30, 30 are provided to secure the die block 25 between said side plates.

The side plates 29, 29 may be welded or otherwise secured to the frame 11 and extend upwardly therefrom in parallel relation with respect to each other. A base plate 31 is shown as being recessed within the side plates 29, 29 at its ends, adjacent the lower end of said side plates and as extending thereacross. Cap screws 32, 32 extending through and having their heads recessed within the side plates 29, 29 are threaded in opposite ends of the base plate 31 to secure said base plate to said side plate and to space said side plates apart at their lower ends.

A back plate 33 is shown as connecting the side plates 29, 29 together. As herein shown, the back plate 33 extends beyond opposite sides of the side plates 29, 29, and is formed with gibs 34, 34 at its ends. The insides of the gibs 34, 34 are abutted by the outer sides of the side plates 29, 29, to accurately maintain said side plates in parallel relation with respect to each other. Cap screws 35, 35 are shown as being provided to secure said back plate to said side plates.

The top cylinder 16 is shown as extending downwardly through and as being secured to a mounting block 37, secured to the bottoms of guide blocks 39, 39 as by cap screws 40, 40. The blocks 39, 39 are each shown as having inwardly extending projecting portions 38, 38 recessed within the side plates 29, 29 and secured thereto by cap screws 41, 41. A collar 43 encircling and secured to the cylinder 16 is shown as abutting the top of the mounting block 37.

A fluid connection 44 is shown as being connected with the mounting block 37 for supplying fluid under pressure to the piston rod end of the cylinder 16, to release the die 17 from the article being held thereby. A fluid connection 45 is provided at the head end of the cylinder 16 for supplying fluid under pressure thereto to hold the die 17 in engagement with the article. The supply and release of fluid under pressure to and from the head and piston rod ends of the cylinder 16 is under control of a valve 46 connected with the pump 15 through a pressure line 42, and mounted on one side plate 29.

The cylinder 16 has a piston (not shown) movable therein having a piston rod 47 extending therefrom and extensible from said cylinder. The lower end of the piston rod 47 is shown as extending within a socketed mounting bracket 49 and as being connected thereto as by a pivot pin 50. The mounting bracket 49 in turn is shown as being secured to the top face of a die block 51 as by cap screws 52, 52. The die block 51 is shown as having the die 17 recessed within the lower face thereof.

A means is provided for guiding the die block 51 and die 17 for rectilinear movement toward and from the die 19, which is herein shown as being two spaced vertically extending guide rods 53, 53 mounted in the die 19 and extending upwardly therefrom and slidably engaging bearing sleeves 54, 54 mounted in the die block 51, adjacent the outer side thereof.

The plate 23 is shown as being slidably guided at its opposite ends along vertically extending channeled guides 55, 55 herein shown as being recessed within the side plates 29, 29 and as extending vertically along the forward end portions of said side plates. The cylinder 21, vertically moving the plate 23 along the channeled guides 55, 55, is shown as having a bifurcated mounting bracket 57, depending from its head end. The furcations of the mounting 57 extend downwardly along opposite sides of a cylinder mounting 59 and are pivotally connected thereto as by a transverse pivot pin 60. The cylinder mounting 59 is shown as being supported on the top surface of the base plate 31, and as being secured thereto as by machine screws 62, 62.

A piston rod 63 extending from a piston (not shown) within the cylinder 21, is shown as extending within a socket 64 depending from the plate 23 for vertically moving said plate along the guides 55, 55.

A fluid connection 65 is shown as being provided to supply fluid under pressure to the head end of the cylinder 21. A fluid connection 66 is shown as being provided to admit fluid under pressure to the piston rod end of the cylinder 21. Fluid under pressure is admitted to either the head or piston rod ends of the cylinder 21 under the control of a valve 69 shown as being mounted on and projecting from the opposite side plate 29 from the valve 46, and as being connected in series with the valve 46.

The valve 69 is shown as being connected with the valve 46, through a pressure line 71 and as being connected with the tank 12, through a return line 72.

Upward movement of the bending plate 23 and the bending die 22 may be limited by a suitable adjustable stopping means herein shown as being two spaced machine screws 73, 73. The machine screws 73, 73 are threaded in the bottom of a spacer bar 74, connected between the forward end portions of the side plates 29, 29, and recessed therein at its ends. Lock nuts 75, 75 are provided to hold the stops 73, 73 in the required position.

The bending die 22 is shown in Figure 3 as being recessed within an upwardly and inwardly opening recess 77, formed in inner upper end portions of the bending plate 23 and as being secured thereto by machine screws 79, 79. The bending die 22 is shown as having an inner bending or working face 80 inclined to conform to the form of the article being formed, and projecting inwardly from the inner face of the plate 23. The inclined die

face 80 of the bending die 22 is also shown as having a uniformly rounded upper engaging end portion 81 engaging beneath the ear or flap 24 upon upward movement of the bending plate 23 and wiping and bending the flap 5 to conform to a recessed die face 83, formed in the die block 51, to form the projection 24 to the form of the face 83, upon clamping of the article 18 between the dies 17 and 19, and upon upward movement of the bending die 22 by the application of fluid under pressure to the head end of the cylinder 21.

In operation of the press, a partially finished link 18, which has first been forged by a drop forge process with the projecting lug 24 extending outwardly in the plane of the upper surface of the link and is then stripped, is placed in the die 19 in the position shown in Figure 3, while at a hot working temperature, with the projection 24 extending into position to be engaged by the face 80 of the bending die 22. Fluid under pressure is then admitted to the head end of the cylinder 16 by operation of the valve 46 to engage the die 17 with the forged link and rigidly hold the link to the die 19. Fluid under pressure may then be admitted to the head end of the cylinder 21 to move the plate 23 and bending die 22 upwardly and wipe the undersurface of the projecting portion 24 of the link with the die face 80, and uniformly bend the projecting portion of the link to conform to the face 83 of the die block 51. The stops 73, 73 may be adjusted to limit vertical movement of the die block to a position where the face thereof exactly conforms to the outer face of an upwardly bent lug or projection 24.

It will be understood that modifications and variations may be effected without departing from the scope of the novel concepts of the present invention.

I claim as my invention:

1. A metal forming press comprising a frame having a base, parallel spaced side walls extending upwardly from said base and a back wall connecting said side walls together, a stationary die mounted between and secured to said side walls and spacing the same apart and having an upwardly facing die face formed to conform to and supportingly receive a partially formed article, a movable die slidably guided in said side walls for movement toward and from said stationary die, said movable die having a die face formed to conform to a partially formed article and adapted to engage the article to be formed with said stationary die and hold the same to said stationary die free from deformation, power means engaging said movable die with the article to be formed, a bending die guided between said side walls and vertically movable from beneath said stationary die in a path intersecting a projecting portion of the article to be formed, said movable die having a recessed die face extending in the general plane of movement of said bending die and said bending die having a cooperating die face wiping the projecting portion of the article to be formed upwardly into engagement with said recessed die face.

2. A metal forming press comprising a frame having a base, parallel spaced side walls extending upwardly from said base, a back wall extending upwardly from said base and connecting said side walls together, a stationary die recessed within said side walls at its ends, said stationary die having guide rods extending upwardly therefrom, a movable die mounted between said side walls and slidably guided on said guide rods, said stationary and movable dies having cooperating die faces conforming to the form of an article to be formed and adapted to engage and hold the article to be formed free from deformation with an end thereof projecting beyond said dies, hydraulic cylinder and piston means mounted between said side plates adjacent the upper ends thereof and having connection with said movable die for vertically moving the same toward and from said stationary die, a bending die, said side plates having recessed guides extending along one side of said stationary and movable dies for slidably receiving

and guiding opposite ends of said bending die, hydraulic cylinder and piston means operatively connected with said bending die for moving the same in a path intersecting the projecting end of the article to be formed, said movable die having a recessed die face extending along one side thereof, and said bending die having a cooperating projecting die face for wiping engagement with a projecting end portion of an article to be formed to wipe the projecting end portion of the article to be formed along said recessed die face.

3. A metal forming press comprising a frame having a base, parallel spaced side walls extending upwardly from said base, a back wall extending upwardly from said base and connecting said side walls together, a stationary die recessed within said side walls at its ends, said stationary die having guide rods extending upwardly therefrom, a movable die mounted between said side walls and slidably guided on said guide rods, said stationary and movable dies having cooperating die faces conforming to the form of an article to be formed and adapted to engage and hold the article to be formed free from deformation with an end thereof projecting beyond said dies, hydraulic cylinder and piston means mounted between said side plates adjacent the upper ends thereof and having connection with said movable die for moving the same toward and from said stationary die, a bending die, said side plates having recessed guides extending along one side of said

stationary and movable dies for slidably receiving and guiding opposite ends of said bending die, hydraulic cylinder and piston means operatively connected with said bending die for moving the same in a path intersecting the projecting end of the article to be formed, said movable die having a recessed die face extending along one side thereof, and said bending die having a cooperating projecting die face movable into said recessed portion to wipe the projecting end portion of the article to be formed into said recessed die face, a tie bar connecting said side plates together adjacent the upper ends thereof, outwardly of said stationary and movable dies, and stopping means on said tie bar in the path of movement of said bending die, and limiting vertical movement thereof.
